Primary Examiner — Darlington Ly*Assistant Examiner* — D. Ryan Tisdale(74) *Attorney, Agent, or Firm* — Sanchelima & Associates, P.A.; Christian Sanchelima; Jesus Sanchelima(57) **CLAIM**

The ornamental design for a boat cover elevating stand, as shown and described.

DESCRIPTION

FIG. 1 is an isometric operational view of a boat cover elevating stand showing my new design;
FIG. 2 is an isometric view thereof;
FIG. 3 is a front elevational view thereof;
FIG. 4 is a rear elevational view thereof;
FIG. 5 is a left side elevational view thereof;
FIG. 6 is a right elevational view thereof;
FIG. 7 is a top plan view thereof; and,
FIG. 8 is a bottom plan view thereof showing my design. The broken lines in the drawings illustrate portions of the boat cover elevating stand which form no part of the claimed design.

1 Claim, 5 Drawing Sheets(56)
